CLAIM

The ornamental design for a side brush, as shown and described.

DESCRIPTION

FIG. 1 is a front elevation view of a side brush showing our new design;

FIG. 2 is a rear elevation view thereof;

FIG. 3 is a side elevation view thereof;

FIG. 4 is a top plan view thereof;

FIG. 5 is a bottom plan view thereof;

FIG. 6 is an top perspective view thereof; and,

FIG. 7 is a bottom perspective view thereof.

1 Claim, 7 Drawing Sheets---
